UNITED STATES PATENT OFFICE.

MILTON J. HELLER, OF NEW YORK, N. Y., ASSIGNOR TO L. HELLER & SON, INC., OF NEW YORK, N. Y., A CORPORATION OF NEW YORK.

DESIGN FOR A JEWEL STONE OR AN ARTICLE OF SIMILAR NATURE.

Application filed February 21, 1925. Serial No. 12,449. Term of patent 3½ years.

To all whom it may concern:

Be it known that I, MILTON J. HELLER, a citizen of the United States, residing at New York city, in the county and State of New York, have invented a new, original, and ornamental Design for a Jewel Stone or Article of Similar Nature, of which the following is a specification, reference being had to the accompanying drawing, forming a part thereof.

In the drawings:

Figure 1 is a plan view of a jewel stone embodying my design.

Figure 2 is an end view thereof; and

Figure 3 is a side view thereof.

I claim:

The ornamental design for a jewel stone or an article of similar nature as shown.

In testimony whereof I affix my signature.

MILTON J. HELLER.
